UNITED STATES PATENT OFFICE.

ANNA L. VILANDRER, OF NEW YORK, N. Y.

DESIGN FOR A CLASP OR HOOK FOR A WAIST-BELT.

59,795.

Specification for Design.

Patented Nov. 22, 1921.

Application filed February 1, 1921. Serial No. 441,681. Term of patent 14 years.

To all whom it may concern:

Be it known that I, ANNA L. VILANDRER, a citizen of the United States, and resident of New York, borough of Manhattan, county of New York, State of New York, have invented a new, original, and ornamental Design for a Clasp or Hook for a Waist-Belt, of which the following is a specification, reference being had to the accompanying drawing, forming part thereof.

Fig. 2 is a section on line 2, 2 in Fig. 1.

Figs. 3 and 4 are perspective views of clasp members of my new design.

I claim:

The ornamental design for a clasp or hook for a waist belt, substantially as shown.

Signed at New York, in the county of New York and State of New York, this 31 day of January, 1921.

ANNA L. VILANDRER.
